DESIGN FOR A COLLAR HOLDER

David Harold Bowder, Attleboro, Mass., assignor to Swank Products, Inc., a corporation of Delaware

Application October 26, 1940, Serial No. 96,107

Term of patent 14 years

To all whom it may concern:

Be it known that I, David Harold Bowder, a citizen of the United States of America, residing at Attleboro, county of Bristol, State of Massachusetts, have invented a new, original, and ornamental Design for a Collar Holder, of which the following is a specification, reference being had to the accompanying drawing, forming a part thereof.

Fig. 1 is a side elevation of a collar holder showing my new design;

Fig. 2 is a top plan view; and

Fig. 3 is a section on line 3—3 of Fig. 1 thereof.

I claim:

The ornamental design for a collar holder, substantially as shown.

DAVID HAROLD BOWDER.
